Primary Examiner — Sheryl Lane*Assistant Examiner* — Ieisha N Price(74) *Attorney, Agent, or Firm* — Rosenberg, Klein & Lee(57) **CLAIM**

The ornamental design for an expansion screw, as shown and described.

DESCRIPTION

FIG. 1 is a top perspective view of the expansion screw, showing our new design;

FIG. 2 is a bottom perspective view thereof;

FIG. 3 is a front elevational thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings illustrate portions of the expansion screw and form no part of the claimed design.

1 Claim, 7 Drawing Sheets(56)
